United States Patent Office

Des. 209,010
Patented Oct. 24, 1967

209,010

PAPER TOWEL HOLDER

Mel Appel, Livingston, and Martin Schnur, West Orange,
N.J., assignors to Elpo Industries Inc., Fair Lawn, N.J., a corporation of New Jersey

Filed Nov. 4, 1966, Ser. No. 4,560

Term of patent 14 years

(Cl. D52—2)

FIG. 4

We claim:

The ornamental design for a paper towel holder, as shown and described.
